UNITED STATES PATENT OFFICE.

CHARLES V. LOGWOOD AND CYRIL F. ELWELL, OF PALO ALTO, CALIFORNIA.

SPACE TELEGRAPHY.

1,195,485.

Specification of Letters Patent. Patented Aug. 22, 1916.

Application filed June 12, 1911. Serial No. 632,536.

To all whom it may concern:

Be it known that we, CHARLES V. Logwood and CYRIL F. ELWELL, citizens of the United States, and residents of Palo Alto, 5 in the county of Santa Clara and State of California, have invented certain new and useful Improvements in Space Telegraphy, of which the following is a specification.

The invention relates to space telegraphy 10 and especially to transmitting systems therefor, wherein the signal is transmitted through the natural media by means of continuous undamped waves of a high frequency.

15 The object of the invention is to provide means for signaling with continuous waves having a frequency higher than the limit of audibility without the use of some special device at the receiving station for reducing 20 the frequency to within the range of audibility.

Another object of the invention is to break up the high frequency wave train into groups having a group frequency within the 25 range of audibility.

Another object of the invention is to provide means for overcoming the effects of static or atmospheric electricity.

This invention relates to an improvement 30 in the Poulsen system of space telegraphy. Such system is the only system to our knowledge which employs a continuous undamped wave of very high frequency, and in such system a "ticker" or interrupter is employed 35 at the receiving station in order that the signals may be received. A receiving station not equipped with a ticker cannot receive messages transmitted by the Poulsen sending station unless the sending station is 40 equipped with an interrupter and this feature is extremely detrimental when in times of distress it is necessary to communicate with every wireless receiving station, regardless of whether it is equipped to receive 45 continuous undamped waves or damped waves of the spark system. In order to overcome this difficulty, we arrange an interrupter in the Poulsen sending circuit which breaks the continuous waves into groups, 50 the group frequency being such that the messages may be received by receiving stations equipped to operate on the spark system.

The effect of this invention is to produce 55 a high piercing note at the receiving station

which will drown out the note produced by atmospheric or static charges.

For the purpose of explaining the invention, we have shown diagrammatically in the accompanying drawings, several forms 60 of connecting up the transmitting apparatus, but it is to be understood that our invention is not to be limited to such forms, as changes may be made in the position of the various elements without varying from 65 the spirit of our invention.

The drawing shows a source of continuous oscillations, directly connected to the antenna, the interrupter being arranged in series with the sending key, which is shunted 70 on part of the inductance.

The source of continuous undamped oscillations is shown as an arc circuit, having a capacity 2 in shunt on the arc 3. Current is supplied to the arc 3 by means of the wires 75 4-5 which emanate from the source of power.

When the antenna is directly connected to the arc circuit, the connection to earth E is made from one side of the arc. 80

The interrupter 8 may be of any suitable form, and in the drawings we have shown a rotatable commutator, which is rotated by any desirable means at a rate to cause a frequency within the limits of audibility. 85

Arranged between the source of oscillations and the antenna is a variable inductance 9. Shunting a portion of the inductance is a circuit containing the sending key 12 and the interrupter 8. When the key is 90 open, the high frequency continuous oscillations are emanating from the antenna continuously, but when the key is closed, these oscillations are modified periodically in intensity and frequency. By shunting a portion 95 of the inductance, the frequency of the continuous waves is varied, but as the spark system receiver is not effected by such high frequency it is of no effect. The spark system receivers are effected only by the group 100 frequency, regardless of the frequency of the high frequency oscillations forming said groups.

The frequency of the continuous oscillations is in excess of 100,000 per second and 105 we find that a group frequency between 500 and 1000 produces efficient results.

When it is desirable to communicate only with stations which are associated with the sending station and which are equipped to 110

receive high frequency continuous oscillations, the interrupter may be cut out and the signals transmitted without breaking the oscillations into groups.

5 We claim:

In a transmission system for space telegraphy, a source of continuous undamped oscillations, a conductor connecting one side of said source to earth, an antenna connected to the other side of said source, an inductance in circuit between the antenna and said source, a circuit adapted to shunt a portion of said inductance and a key and interrupter in said shunt circuit.

CHARLES V. LOGWOOD.
CYRIL F. ELWELL.
